UNITED STATES PATENT OFFICE.

LUCILLE BUHL-BONANNO, OF MOUNT VERNON, NEW YORK, ASSIGNOR TO LUCILLE BUHL VANITY PRODUCTS CO., INC., OF NEW YORK, N. Y., A CORPORATION OF NEW YORK.

LIP STICK.

Application filed March 21, 1925. Serial No. 17,158.

To all whom it may concern:

Be it known that I, LUCILLE BUHL-BONANNO, a citizen of the United States, residing at Mount Vernon, in the county of Westchester and State New York, have invented certain new and useful Improvements in Lip Sticks, of which the following is a specification.

This invention relates to improvements in lipsticks. The principal object thereof is to provide a combination lipstick in which one half of the lipstick consists of cold cream, which has a soothing but not a coloring effect upon the skin, and the other half consists of rouge for coloring the lips.

A further object of this invention is to provide a combination lipstick in which the cold cream and rouge form adjacent lateral portions of the same lipstick, instead of being placed end to end, so that it is possible to provide a combination lipstick with these double properties, of the same length as the ordinary lipstick.

Further objects of the invention will be apparent from the specification and drawings in which—

Fig. 1 is a perspective view of the container for my improved lipstick.

Fig. 2 is a perspective view of the container and improved lipstick therein with the cover removed.

Fig. 3 is a perspective view of the cover only.

Fig. 4 is an enlarged view of the lipstick and holder.

Fig. 5 is a sectional view of the lipstick and holder.

Fig. 6 is a section along the line 6—6 of Fig. 4.

For various reasons it is desirable that only one end of the lipstick be exposed as the material of which lipsticks are composed is fragile and likely to gather dust and for this reason I have deemed it desirable to provide a lipstick in which only one end thereof is exposed and in which the cold cream and rouge may be applied almost simultaneously, without reversing the lipstick or removing it from its holder.

In the drawings, A represents the metallic holder for my combination lipstick, and B the metallic cover therefor. I have design-

nated the cold cream portion of the lipstick as C, and the rouge portion as D. The end of the lipstick is inserted into a separate metallic cup E having the button F traveling in the slot G. The cold cream and rouge in order to be effective, must be composed of soft unctuous materials which will adhere to the skin, but on the other hand, means must be provided so that the rouge and cold cream will not flow and coalesce into each other. To achieve this object, I have provided a thin diaphragm or separator H which extends along the entire length of the lipstick and which may be made of waterproof paper, metal foil or of a similar substance. The lipstick is provided with a coating on the outside of tinfoil K which may be torn off as the material is used up.

Having fully described my invention, what I claim is:

1. A cosmetic consisting of a semi-cylindrical body of cold cream and a semi-cylindrical body of rouge adjacent each other and in a common wrapper and a cylindrical metal container therefor.

2. In a cosmetic, the combination of a stick of cold cream and a stick of rouge separated from each other, but in a common wrapper.

3. A combination lipstick comprising a rouge portion and a cold cream portion laterally adjacent each other and separating means intermediate the same, said rouge portion and said cold cream portion contacting with said separating means to form a single composite body.

4. A combination lipstick comprising a hollow cylindrical container, a stick of cold cream and a stick of rouge adjacent each other and in a common wrapper, means separating the rouge and the cold cream so as to prevent the coalescence of the two and means for simultaneously exposing the ends of the rouge and of the cold cream.

5. In a cosmetic, the combination of a semi-cylindrical stick of rouge, and a semi-cylindrical stick of cold cream adjacent thereto and separated from the rouge by a non-permeable diaphragm and a common wrapper for said rouge and cold cream.

In testimony whereof I affix my signature.

LUCILLE BUHL-BONANNO.
